ATTORNEY

996,169. ROTARY ENGINE. JOHN HERBERT VAN DEVENTER, Buffalo, N. Y.
Filed July 29, 1910. Serial No. 574,576.

To all whom it may concern:

Be it known that I, JOHN HERBERT VAN DEVENTER, a citizen of the United States of America, residing at Buffalo, in the county of Erie and State of New York, have invented certain new and useful Improvements in Rotary Engines, of which the following is a full, clear, and exact description.

My invention relates to rotary engines having one or more pairs of rotors and more particularly to rotary engines with rotors each having a plurality of spirally disposed and intermeshing blades.

Among the objects of my invention are, to provide a rotary motor which is very compact, of very few parts, and of comparatively high power for its size; also one which shall be smooth running and provide a uniform speed and torque. Moreover the blades on the rotors of my engine are of such a number and disposed at such an angle to the axis of the same, that the cross section of each presents a true spur gear, thus securing transmission of rotation and power from one rotor to the other and obviating the necessity of employing a pair of auxiliary gears. These and many other advantages, which will be apparent to those skilled in the art, have been accomplished by the device herein shown and described.

In the specification and the appended claims the term fluid will be used but obviously my engine is applicable to be driven with either compressed air or steam as well as any fluid under pressure.

Reference is to be had to the accompanying drawings which form part of this specification.

In the drawings like characters of reference indicate like parts in the different views of which:

Figure 1 is a sectional elevation of the casing in the preferred form of my engine and shows the rotors partly in section and partly in elevation. Fig. 2 is a sectional ele-

vation taken on line A—B of Fig. 1. Fig. 3 is a vertical sectional view of the inlet port and the throttle and is taken on line C—D of Fig. 1. Fig. 4 is a horizontal sectional view of the inlet port and the throttle and is taken on line E—F of Fig. 3. Fig. 5 is a diagrammatical view showing a pair of rotors with fluid inlet at each end, thus making the engine reversible. Fig. 6 is a diagrammatical sectional end view taken on line G—H of Fig. 5. Fig. 7 is a diagrammatical view of a modified form of rotors arranged to have the fluid inlet at the middle instead of at the end. Fig. 8 is a diagrammatical sectional view taken on the line I—J of Fig. 7. Fig. 9 is a dia-

grammatical view of two pairs of rotors coupled on the same shafts with the fluid inlet at the outer end of each and the exhaust between the inner ends of each pair, thus balancing the end thrust. Fig. 10 is a diagrammatical view of two pairs of rotors arranged to give a two-stage or tandem effect. Fig. 11 is a diagrammatical view of a single unit comprising three pairs of rotors of different sizes and having one shaft in common thus producing a three-stage effect.

In the drawings, Figs. 1 to 4, 12 is the engine casing which is provided with suitable feet or bearing surfaces 36. 13 is the front head and 14 the rear head. 15 are the rotors and the casing 12 preferably surrounds the rotors, as shown in Fig. 2, at all points but where the rotors mesh and that portion of the rear side of the casing which is between the planes of the axes of the rotors, where a screw-threaded aperture 16 is provided through which the exhaust from the engine may be carried off. While the casings closely fit the rotors and surround them as above stated, all that is necessary for the successful operation of the engine is that the fluid be confined between the blades until each has finished its cycle. All that is required for this is a narrow rib similar to that shown in Fig. 8 at 75 and obviously the case surrounding the rotors may be omitted entirely if desired. The front head is provided with bearings 17 and 18 and the rear head with bearings 19 and 20 each of which is provided with an anti-friction metal bushing 21 and an oil reservoir 22. Rotatably mounted in the bearings 17 and 19 is the upper rotor shaft 23 and in a like manner the lower rotor shaft 24 is rotatably mounted in bearings 18 and 20. Each of the said bearings is provided with an oil ring or chain 25 which dips into the oil contained in the oil reservoir 22 and constantly supplies these bearings with the proper amount of oil. The outer end of each of the bearings 19 and 20 is internally screw-threaded and into the screw-thread in bearing 19, fits a

thrust plug 26. This plug is provided with a central aperture which fits over a reduced peripheral diameter on the shaft 23 and between the inner face of the plug 26 and the shoulder 27 on the shaft 23, is disposed a thrust bearing 28. An interior annular groove 29 is provided in the plug 26 in which fits a suitable packing 30. A lock nut 31 serves to lock the plug 26 in place when it is properly adjusted. Fitting into the screw-thread in the bearing 20 is a thrust plug 32, between the inner face of which and the end of the shaft 24 is placed a thrust bearing 33. A lock nut 34 secures the thrust plug 32 in place. The outer ends of the bearings 17 and 18 are closed by means of the plates 35. Mounted upon each of the shafts 23 and 24 is a rotor 15. These rotors

are fixed against rotation and end motion on their respective shafts by any of the many suitable means well known in the art. The inlet end of each of the rotors bears against the front head 13 and while thus closing the ends of the said rotors this also seals them more effectively against leakage of the fluid under pressure at this point. The periphery of each of the rotors is provided with a plurality of blades or teeth 37. These blades make an acute angle with the axis of the rotor and they are preferably formed by milling grooves in the periphery of the rotors in much the same manner as the cutting of a spur gear. As shown in Fig. 2, a cross section of each rotor presents a perfect spur gear and the rule governing the number of teeth in a spur gear would apply for the number of blades or teeth on the rotors; for instance, the rotors should never have less than twelve teeth each. These blades may be of the standard gear-tooth shape or any other suitable section but the preferred form is shown in Fig. 2. In this figure it will be seen that the faces and the top of each tooth form substantially a semi-circle; the flanks of each tooth are formed in substantially the arcs of a circle so that the two flanks of adjoining teeth form substantially a semi-circle; and also the sides of each tooth at the pitch line, where its faces and flanks join, for a distance not greater than one-quarter its full height, are substantially straight. This form of tooth will more effectually seal the blades against leakage of the fluid under pressure and thus make the engine more efficient in operation. 38 is the admission port and 39 the admission port casing which is preferably integral with the front head 13 and provided at its outer end with an interior screw-thread to which may be attached the fluid supply pipe. A groove 40, greater in width than the diameter of the admission port 38, is made in the head 13 from the inner face thereof and this groove extends past the inner end of the admission port 38. Slidably disposed within the groove 40 is a slide 41 by means of which the amount of fluid passing through the port may be regulated. The slide 41 has attached thereto a rod 42 which passes up through a stuffing box gland 43 and may be operated manually but preferably automatically in any of the many ways well known to those skilled in the art, thus providing a governor for the speed of the engine. A port-hole plate 44 is set in flush with the inner face of the head 13 and it is in sliding contact with the slide 41. Through the port-hole plate is a V-shaped aperture 45 the sides of the V being curved equal to the radius of the rotors and the width substantially equal to the height of the blade or less, according to the pressure of the fluid. Thus the pressure of the fluid is made to bear at the most effectual point and

as this port-hole plate is a separate part, it may be easily replaced by one with a different width aperture, hence the engine may be readily adapted for any pressure.

Obviously, the engine may be constructed with a fluid inlet at both ends of the rotors and thus make the engine reversible. This is clearly shown in a diagrammatical manner in Figs. 5 and 6 where 46 and 47 represent the rotors, and 48 and 49, their respective shafts. 50 and 51 represent the inlets for the fluid pressure, thus when the fluid is being forced through the inlet 50 the rotors will revolve in the direction indicated by the arrows 52 but when the fluid is forced through the inlet 51, the direction of rotation will be as indicated by the arrows 53.

In Figs. 7 and 8 I have shown a modified form of my invention where a right hand spiral rotor 54 and a left hand spiral rotor 55 are mounted upon the same shaft and have disposed between them a short straight bladed rotor or spur gear 56. The blades in the rotor 56 are equal in number and are in register with the blades in the rotors 54 and 55. 75 represents a rib which covers only a portion of the peripheries of the rotors and is provided with a fluid inlet 57 which is disposed at the center or in line with the rotors 56. Thus the fluid enters the rotors 56 and is forced out in both directions through the right hand and left hand spiral rotors 54 and 55 thereby exerting a pressure in opposite directions from the center and thereby balancing the end thrust. In Fig. 9 a pair of right hand and left hand spiral rotors are also employed but with two fluid inlets 58 and 59, the fluid exhausting between the inner ends of the rotors.

In Fig. 10 a diagram of a two-stage effect is shown, 60 being the inlet for the first stage of rotors 61 and 62, and 63 the inlet for the second stage of rotors 64 and 65. Fluid under its initial pressure may be forced through both inlets or the exhaust from the first stage may be utilized to propel the second stage.

In Fig. 11 is shown in a diagrammatical manner, a three-stage or triple-expansion effect. 66 and 67 represent the first stage of rotors and 68 their inlet; 69 and 70 the second stage of rotors and 71 their inlet; and 72 and 73 the third stage of rotors and 74 their inlet. Either the right hand or the left hand rotor of each stage are connected together and preferably have one shaft in common. The fluid under pressure enters the first stage at 68, the exhaust from the first stage forms the supply for the second stage and the exhaust from the second stage, the supply for the third stage, as indicated by the arrow running through the three stages. In this type of rotary engine the rotors increase in size from the first stage to the third.

Having thus described my invention, I will now describe its operation.

Referring to Fig. 5, 76 represents the point of mesh of the blades 77 and 78. Now suppose fluid under pressure is admitted through the inlet 50, this fluid will impinge against the blades 77 and 78, not in a direction at right angles to the blades, but substantially parallel to them and directly toward the point of mesh. This results in causing the point 76 and the bucket formed thereat to recede toward the exhaust end of the rotors and thus cause the said rotors to revolve in opposite directions. The cycle of a pair of blades begins with the first impact of the fluid against them at the moment that the bucket is formed, and is completed when the point of mesh or the bucket formed by the same pair of blades reaches the exhaust end of the rotors. The less the spiral angle, or the angle which each blade makes with the plane through the axis of the rotor, the greater will be the rate of recession of point of mesh toward the exhaust end of the rotors. As this is equivalent to the "bucket velocity" in a turbine, and as the efficiency of a turbine depends to a large extent, upon the velocity of its buckets, I am therefore able, by making the spiral angle small, to secure a high bucket velocity and a resulting high efficiency with a low rotative speed.

In Fig. 3 it will be seen that the port hole 45 exposes several of the blades at the same time and as one pair of blades starts its cycle before the one or two preceding pairs have finished their cycle, this construction, which is equivalent to a plurality of jets, keeps each working pair of blades under the pressure of the fluid until the point of cut-off is reached. The point of cut-off is reached on a pair of blades when the admission end of said pair of blades has passed the outer extremity of the V-shaped port

hole 45. From the point of cut-off until the time of exhaust the volume of fluid inclosed in said pair of blades expands. The ratio of expansion is determined by the distance from the extremities of the V-shaped port hole to the center line of the rotors, this ratio being made greater as the port hole is extended. The fluid of course has accomplished its effective work on any pair of blades when the point of mesh of such pair of blades has reached the ends of the rotors opposite to the inlet, but to reduce leakage to a minimum, the fluid contained between the blade just finishing its cycle and the one adjoining it, is carried preferably around between the rotor and the casing 12 for substantially 270° from the point where the bucket is formed and the cycle commences.

Obviously this invention may be applied to any use where a prime mover is desired and in thus adapting it to the various uses indicated, modifications may be made which

will embody the spirit and essence of the invention and some specific details without departing from the invention as herein disclosed.

Having thus described my invention, what I claim is:

1. In a rotary engine the combination of a pair of rotors rotatively mounted and each provided with a plurality of spirally disposed and intermeshing tooth blades formed with semi-circular tops, semi-circular faces and straight sides connecting said semi-circular tops and said semi-circular faces, said blades forming acute angles with the axes of said rotors.

2. In a rotary engine the combination of a pair of rotors each provided with a plurality of spirally disposed and intermeshing tooth blades, said blades forming acute angles with the axes of said rotors, a rib extending across the inlet side of said rotors parallel to their axes and in conformity to a portion of their peripheries, front and rear heads, bearings carried by said front and rear heads, shafts rigidly secured in said rotors and rotatably mounted in said bearings, the inlet ends of said rotors being in contact with said front head, and means carried by said front head whereby one or more jets of fluid under pressure may be made to impinge on said blades.

3. In a rotary engine the combination of a pair of rotors each provided with a plurality of spirally disposed and intermeshing tooth blades, said blades forming acute angles with the axes of said rotors, a casing surrounding said rotors, a rib integral with said casing extending across the inlet side of said rotors, parallel to their axes and in conformity to a portion of their peripheries, front and rear heads fitted to said casing, bearings carried by said front and rear

heads, shafts rigidly secured in said rotors and rotatably mounted in said bearings, the inlet ends of said rotors being in contact with said front head, and means carried by said front head whereby one or more jets of fluid under pressure may be made to impinge on said blades.

4. In a rotary engine the combination of a pair of rotors each provided with a plurality of spirally disposed and intermeshing tooth blades, said blades forming acute angles with the axes of said rotors, a casing surrounding said rotors, a rib integral with said casing extending across said inlet side of said rotor, parallel to their axes and in conformity to a portion of their peripheries, front and rear heads fitted to said casing, bearings carried by said front and rear heads, shafts rigidly secured in said rotors and rotatably mounted in said bearings, the inlet ends of said rotors being in contact with said front head, an inlet port in said front head, and one or more jets of fluid

under pressure leading from said port and impinging upon said blades.

5. In a rotary engine the combination of a pair of rotors each provided with a plurality of spirally disposed and intermeshing tooth blades, said blades forming acute angles with the axes of said rotors, a casing surrounding said rotors, a rib integral with said casing extending across the inlet side of said rotors, parallel to their axes and in conformity to a portion of their peripheries, front and rear heads fitted to said casing, bearings carried by said front and rear heads, shafts rigidly secured in said rotors and rotatably mounted in said bearings, the inlet ends of said rotors being in contact with said front head, an inlet port in said front head, a V-shaped aperture communicating with said inlet port and disposed in said front head opposite the point of mesh of said rotors, whereby fluid under pressure may be made to impinge upon said blades.

6. In a rotary engine the combination of a pair of rotors each provided with a plurality of spirally disposed and intermeshing tooth blades, said blades forming acute angles with the axes of said rotors, a casing surrounding said rotors, a rib integral with said casing extending across the inlet side of said rotors, parallel to their axes and in conformity to a portion of their peripheries, front and rear heads fitted to said casing, bearings carried by said front and rear heads, shafts rigidly secured in said rotors and rotatably mounted in said bearings, the inlet ends of said rotors being in contact with said front head, an inlet port in said front head, an interchangeable port-hole plate disposed in said front head, flush with the inner face thereof and between said inlet port and the said rotors, a V-shaped port through said port-hole plate whereby fluid under pressure may be made to impinge on said blades.

7. In a rotary engine the combination of a pair of rotors each provided with a plurality of spirally disposed and intermeshing tooth blades, said blades forming acute angles with the axes of said rotors, a casing surrounding said rotors, a rib integral with said casing extending across the inlet side of said rotor, parallel to their axes and in conformity to a portion of their peripheries, front and rear heads fitted to said casing, bearings carried by said front and rear heads, shafts rigidly secured in said rotors and rotatably mounted in said bearings, the inlet ends of said rotors being in contact with front head, an inlet port in said front head, one or more jets of fluid under pressure leading from said inlet port and impinging upon said blades, and regulating means disposed between said inlet port and said jet or jets whereby the speed of the rotors may be governed.

8. In a rotary engine the combination of a pair of rotors each provided with a plurality of spirally disposed and intermeshing tooth blades, said blades forming acute angles with the axes of said rotors, a casing surrounding said rotors, a rib integral with said casing extending across the inlet side of said rotors, parallel to their axes and in conformity to a portion of their peripheries, front and rear heads fitted to said casing, bearings carried by said front and rear heads, shafts rigidly secured in said rotors and rotatably mounted in said bearings, the inlet ends of said rotors being in contact with said front head, thrust bearings disposed in said rear head, an inlet port in said front head, an interchangeable port-hole plate disposed in said front head, flush with the inner face thereof and between said inlet port and the said rotors, a V-shaped port through said port-hole plate whereby fluid under pressure may be made to impinge on said blades.

9. In a rotary engine the combination of a pair of rotors each provided with a plurality of spirally disposed and intermeshing tooth blades, said blades forming acute angles with the axes of said rotors, a casing surrounding said rotors, a rib integral with said casing extending across the inlet side of said rotors, parallel to their axes and in conformity to a portion of their peripheries, front and rear heads fitted to said casing, bearings carried by said front and rear heads, shafts rigidly secured in said rotors and rotatably mounted in said bearings, the inlet ends of said rotors being in contact with said front head, an inlet port in said front head, an interchangeable port-hole plate disposed in said front head, flush with the inner face thereof and between said inlet port and said rotors, a V-shaped port through said port-hole plate, a slide disposed in said front head and slidable on the inner face of said port-hole plate and means connecting with said slide whereby fluid under pressure may impinge upon said blades and the amount of fluid passing through said V-shaped port-hole may be regulated and the speed of the rotors governed.

10. In a rotary engine the combination of a pair of rotors each provided with a plurality of spirally disposed and intermeshing tooth blades, said blades forming acute angles with the axes of said rotors, a casing surrounding said rotors and having its inner wall in conformity with the periphery of each said rotor for substantially 270° , starting from the point of mesh of said blades and extending around from the inlet side of said rotors, an exhaust port in the side of said casing opposite the inlet side of said rotors, front and rear heads fitted to said casing, bearings carried by said heads, shafts rigidly secured in said rotors and rotatably mounted in said bearings, the inlet end of said rotors being in contact with said front

head, an inlet port in said front head and one or more jets of fluid under pressure leading from said port and impinging upon said blades.

11. In a rotary engine the combination of a pair of rotors each provided with a plurality of spirally disposed and intermeshing tooth blades, said blades forming acute angles with the axes of said rotors, a casing surrounding said rotors and having its inner wall in conformity with the periphery of each said rotor for substantially 270° , starting from the point of mesh of said blades and extending around from the inlet side of said rotors, an exhaust port in the side of said casing opposite the inlet side of said rotors, front and rear heads fitted to said casing, bearings carried by said heads, shafts rigidly secured in said rotors and rotatably mounted in said bearings, the inlet end of said rotors being in contact with said front head, an inlet port in said front head, a V-shaped aperture communicating with said inlet port and disposed in said front head opposite the point of mesh of said rotors, whereby fluid under pressure may be made to impinge upon said blades.

12. In a rotary engine the combination of two or more pairs of rotors each provided with a plurality of spirally disposed and intermeshing tooth blades, said blades forming acute angles with the axes of said rotors, casings surrounding said rotors, a rib integral with said casings extending across the inlet side of said rotors parallel to their axes and in conformity to a portion of their peripheries, front and rear heads fitted to said casing or casings, bearings carried by said front and rear heads, shafts rigidly secured in said rotors and rotatably mounted in said bearings, one or both of said rotors of each pair having a shaft in common, the inlet ends of each pair or pairs of rotors being in contact with said front head or heads, and means carried by said front head or heads whereby one or more jets of fluid under pressure may be made to impinge on the said blades of each pair of rotors.

13. In a rotary engine the combination of two or more pairs of rotors each provided with a plurality of spirally disposed and intermeshing tooth blades said blades forming acute angles with the axes of said rotors, casings surrounding said rotors, a rib integral with said casings extending across the inlet side of said rotors parallel to their axes and in conformity to a portion of their peripheries, front and rear heads fitted to said casings, bearings carried by said front and rear heads, shafts rigidly secured in said rotors and rotatably mounted in said bearings, one or both of said rotors of each pair having a shaft in common, the inlet ends of each pair or pairs of rotors being in contact

with said front head or heads, an inlet port in each said front head, and one or more jets of fluid under pressure leading from said port or ports, and impinging upon the said blades of each pair of rotors.

14. In a rotary engine the combination of two or more pairs of rotors each provided with a plurality of spirally disposed and intermeshing tooth blades said blades forming acute angles with the axes of said rotors, casings surrounding said rotors, a rib integral with said casings extending across the inlet side of said rotors parallel to their axes and in conformity to a portion of their peripheries, front and rear heads fitted to said casings, bearings carried by said front and rear heads, shafts rigidly secured in said rotors and rotatably mounted in said bearings one or both of said rotors of each pair having a shaft in common, the inlet ends of each pair or pairs of rotors being in contact with said front head or heads, an inlet port in each said front head, a V-shaped aperture communicating with said inlet port and disposed in each said front head opposite the point of mesh of said rotors, whereby fluid under pressure may be made to impinge upon the said blades of each pair of rotors.

15. A rotary engine comprising a pair of rotors rotatively mounted and each provided with a plurality of spirally disposed and intermeshing tooth blades, the faces and top of each said tooth blade forming substantially a semi-circle, the flanks of each

said tooth blade being formed in substantially the arcs of a circle so that the two flanks of adjoining tooth blades form substantially a semi-circle and the sides of said tooth blades at or near the pitch line, where the faces and flanks join, being formed substantially straight for a short distance.

16. In a rotary engine the combination of two or more pairs of rotors each provided with a plurality of spirally disposed and intermeshing tooth blades said blades forming acute angles with the axes of said rotors, casings surrounding said rotors, a rib integral with said casings extending across the inlet side of said rotors parallel to their axes and in conformity to a portion of their peripheries, front and rear heads fitted to said casings, bearings carried by said front and rear heads, shafts rigidly secured in said rotors and rotatably mounted in said bearings, one or both of said rotors of each pair having a shaft in common, the inlet ends of each pair or pairs of rotors being in contact with said front head or heads, an inlet port in each said front head, an interchangeable port-hole plate disposed in each said front head, flush with the inner face thereof and between said inlet port and the said rotors, a V-shaped port through

each said port-hole plate whereby fluid under pressure may be made to impinge on the said blade of each pair of rotors.

17. In a rotary engine the combination of two or more pairs of rotors each provided with a plurality of spirally disposed and intermeshing tooth blades, said blades forming acute angles with the axes of said rotors, casings surrounding said rotors, a rib integral with said casings extending across the inlet side of said rotors parallel to their axes and in conformity to a portion of their peripheries, front and rear heads fitted to said casings, bearings carried by said front and rear heads, shafts rigidly secured in said rotors and rotatably mounted in said bearings one or both of said rotors of each pair having a shaft in common, the inlet ends of each pair or pairs of rotors being in contact with said front head or heads, an inlet port in each said front head, one or more jets of fluid under pressure leading from each said inlet port and impinging upon the said blades of each pair and regulating means disposed between said inlet port and said jet or jets, whereby the speed of the rotors may be governed.

18. In a rotary engine the combination of two or more pairs of rotors each provided with a plurality of spirally disposed and intermeshing tooth blades, said blades forming acute angles with the axes of said rotors, casings surrounding said rotors, a rib integral with said casings extending across the inlet side of said rotors parallel to their axes and in conformity to a portion of their peripheries, front and rear heads fitted to said casings, bearings carried by said front and rear heads, shafts rigidly secured in said rotors and rotatably mounted in said bearings, one or both of said rotors of each pair having a shaft in common, the inlet ends of each pair or pairs of rotors being in contact with said front head or heads, thrust bearings disposed in each said rear head, an inlet port in each said front head, an interchangeable port-hole plate disposed in each said front head, flush with the inner face thereof and between said inlet port and the said rotors, a V-shaped port through each said port-hole plate whereby fluid under pressure may be made to impinge on the said blade of each pair of rotors.

19. In a rotary engine the combination of two or more pairs of rotors each provided with a plurality of spirally disposed and intermeshing tooth blades, said blades forming acute angles with the axes of said rotors, casings surrounding said rotors, a rib integral with said casings extending across the inlet side of said rotors parallel to their axes and in conformity to a portion of their peripheries, front and rear heads fitted to said casings, bearings carried by said front and rear heads, shafts rigidly secured in

said rotors and rotatably mounted in said bearings, one or both of said rotors of each pair having a shaft in common, the inlet ends of each pair or pairs of rotors being in contact with said front head or heads, an inlet port in each said front head, an interchangeable port-hole plate disposed in each said front head, flush with the inner face thereof and between said inlet port and each pair of rotors, a V-shaped port through each said port-hole plate, a slide disposed in one or more of said front heads and slidably on the inner face of one or more of said port-hole plates, and means connecting with said slide or slides whereby fluid under pressure may impinge upon the said blades of each pair of rotors and the amount of fluid passing through said V-shaped port-holes may be regulated and the speed of the rotors governed.

20. In a rotary engine the combination of two or more pairs of rotors each provided with a plurality of spirally disposed and intermeshing tooth blades, said blades forming acute angles with the axes of said rotors, casings surrounding said rotors and having their inner walls in conformity with the periphery of each said rotor for substantially 270° , starting from the point of mesh of said blades and extending around from the inlet side of said rotors, an exhaust port in the side of each said casing opposite the inlet side of said rotors, front and rear heads fitted to each said casing, bearings carried by said heads, shafts rigidly secured in said rotors and rotatably mounted in said bearings, one or both rotors of each pair having a shaft in common, the inlet end of each pair of said rotors being in contact with each said front head, an inlet port in each said front head, and one or more jets of fluid under pressure leading from each said port impinging upon said blades.

21. In a rotary engine the combination of two or more pairs of rotors each provided with a plurality of spirally disposed and intermeshing tooth blades, said blades forming acute angles with the axes of said rotors, casings surrounding said rotors and having their inner walls in conformity with the periphery of each said rotor for substantially 270° , starting from the point of mesh of said blades and extending around from the inlet side of said rotors, an exhaust port in the side of each said casing opposite the inlet side of said rotors, front and rear heads fitted to each said casing, bearings carried by said heads, shafts rigidly secured in said rotors and rotatably mounted in said bearings, one or both rotors of each pair having a shaft in common, the inlet end of each pair of said rotors being in contact with each said front head, an inlet port in each said front head, a V-shaped aperture communicating with said

inlet port and disposed in each said front head opposite the inlet port and disposed in each said front head opposite the point of mesh of said rotors, whereby fluid under pressure may be made to impinge upon the said blades of each pair of rotors.

22. In a rotary engine the combination of two or more pairs of rotors, each pair greater in diameter than the one preceding it, each rotor provided with a plurality of spirally disposed and intermeshing tooth blades, said blades forming acute angles with the axes of said rotors, casings surrounding said rotors, a rib integral with said casings extending across the inlet side of said rotors, parallel to their axes and in conformity to a portion of their peripheries, front and rear heads fitted to said casings, bearings carried by said front and rear heads, shafts rigidly secured in said rotors and rotatably mounted in said bearings, one rotor of each pair on the same side of the engine having one shaft in common, fluid inlet means carried by the said front head of the smallest pair of rotors and means carried by the said front heads and rear heads of the casings surrounding the other pairs of rotors, whereby the exhaust fluid from the first pair is made to impinge on the blades of the next pair and a multistage effect produced.

23. A rotary engine comprising a pair of rotors rotatively mounted and each provided with a plurality of spirally disposed and intermeshing tooth blades, the faces and top of each of said tooth blades forming substantially a semi-circle, the flanks of each tooth blade being formed in substantially the arcs of a circle so that the two flanks of adjoining tooth blades form substantially a semi-circle and the said tooth blades being of such proportions relative to the diameters of said rotors that the length of the line of contact of the intermeshing teeth will be substantially equivalent to the entire perimeter of one of said tooth blades.

24. In a rotary engine the combination of a pair of rotors each provided with a plurality of spirally disposed and intermeshing tooth blades, rotor shafts, bearings in which said rotor shafts may be mounted, a rib, a front head in contact with the outer ends of said rotors, and a port so placed with reference to said rotors that admission of the motive fluid into any tooth bucket is substantially discontinued before said tooth bucket has developed its full volume, thereby allowing the contained fluid to expand from this point to the point where the said tooth bucket develops the full volume.

25. In a rotary engine the combination of a pair of rotors each provided with a plurality of spirally disposed and intermeshing tooth blades, a casing surrounding said rotors, a rib which covers only a portion of the

peripheries of said rotors and which is provided with a fluid inlet said inlet being so placed with reference to said rotors that admission of the motive fluid into the tooth bucket is substantially discontinued before said tooth bucket has developed its full volume, rotor shafts and bearings in which said rotor shafts may be mounted, one of said shafts being rigidly secured in one of said rotors.

26. A rotary engine comprising a pair of rotors rotatably mounted and each provided with a plurality of spirally disposed and intermeshing tooth blades, the faces and top of each of said tooth blades forming substantially a semi-circle, the flanks of each tooth blade being formed in substantially the arcs of a circle so that the two flanks of adjoining tooth blades form substantially a semi-circle and the said tooth blades being of such proportion relative to the diameters of said rotors that the contact of the intermeshing teeth will be substantially a line contact at any instant.

In testimony whereof I have hereunto set my hand in the presence of two witnesses.

JOHN HERBERT VAN DEVENTER.
